UNITED STATES PATENT OFFICE.

FRANK RUSSELL GLASENER, OF CEDAR FALLS, IOWA.

LOADING DEVICE FOR MIXING-MACHINES.

1,335,435.

Specification of Letters Patent. Patented Mar. 30, 1920.

Application filed May 29, 1919. Serial No. 300,694.

To all whom it may concern:

Be it known that I, FRANK RUSSELL GLASENER, a citizen of the United States of America, and a resident of Cedar Falls, 5 Blackhawk county, Iowa, have invented certain new and useful Improvements in Loading Devices for Mixing-Machines, of which the following is a specification.

My invention relates to improvements in 10 concrete mixers, and the object of my improvement is to provide for a rotatable mixing-device supported on means for transportation, a loading device, and tiltable slideway on which the latter may be 15 slidingly moved and tilted to a delivery position, said loading device and said mixing-device both operable by the same power-plant mounted on the means for transportation.

20 This object I have accomplished by the means which are hereinafter described and claimed, and which are illustrated in the accompanying drawings, in which Figure 1 is a side elevation of a motor-propelled truck on which is mounted a concrete mixing-drum and my improved loading-device therefor; Fig. 2 is a plan of said truck and mixing-drum, with the loading-device and other parts removed or broken away; Figs. 25 3 and 4 are respectively front and rear elevations of the same devices, with parts removed or broken away, and showing different positions of the loading device, and Fig. 30 5 is a plan of the vessel forming part of the loading device.

35 In said drawings, similar numerals of reference denote corresponding parts throughout the several views.

The numeral 1 denotes a horizontal rectangular frame mounted on carrying-wheels 40 2 and 3 at front and rear.

A power-plant (not shown) is positioned 45 on the forward part of said frame to rotate the power-shaft 4. The latter drives differential-gearing (also not shown) in a gear-case 14, with the alined shaft-parts 15. The latter carry at their outer ends sprocket-pinion 16, and sprocket-chains 17 connect 50 said pinions with sprocket-wheels 18 fixed on the rear carrying-wheels 3.

7 and 10 are transversely alined but independent shafts rotatably mounted on the

forward part of said frame. The shaft 7 carries on its outer end a belt-wheel 8, which may be used in the actuation of machinery, 55 and on its inner end a bevel-pinion 6. On the inner end of the other shaft 10 is a bevel-pinion 9. Said shaft also carries a bevel-pinion 69, and on its outer end a combined winding-drum and band-brake drum 11, 60 which may be employed in actuating hoisting mechanism.

A counter-shaft 13 is rotatably mounted longitudinally in said frame and carries at 65 its forward end a bevel-gear 12 in constant mesh with the bevel-pinion 69.

A bevel-gear 5 is slidably non-rotatably mounted upon the power-shaft 4 and may be disconnectibly meshed with said bevel-pinions 6 and 9.

Upon the rear part of the frame 1 is fixed an erect skeleton frame 33 formed of standards on each side connected by means of longitudinal bars. Within said frame 33 a mixing-drum 25 is mounted on rollers 31 75 on brackets 32 to rotate on a horizontal and longitudinal axis. Said drum 25 has central circular receiving and delivery openings 26 and 27 respectively in its front and rear end heads.

The numeral 24 denotes a spur-gear ring secured medially about the circumferential periphery of said drum. On the rear end of the counter-shaft 13 is fixed a clutch-member 20. A shaft-part 22 is alined with 85 said counter-shaft and has a clutch-member 21 slidably non-rotatably mounted on its forward end and adapted to be disconnectibly meshed with the clutch-member 20. A spur-pinion 23 on the rear end of the 90 shaft 22 is in constant mesh with said gear-ring 24.

A short shaft 70 in said frame 1 carries 95 on its inner end a bevel-gear 38 in constant mesh with a bevel-pinion 19 on the shaft 13. On the outer end of said shaft 70 is fixed a combined winding-drum 39 and band-brake drum 40, the latter carrying a band-brake 41 actuated by means of the usual pivoted arm 42, link 71 and hand-lever 43.

In transversely alined bearings 48 on the frame 33 is rotatably mounted a shaft 46 carrying medially a winding-drum 47 upon 100 which is wound a cable 49. Upon one end

of the shaft 46 is fixed a winding-drum 45, and a cable 44 is connected between said winding-drums 39 and 45 to unwind from one of them while being wound up on the other, and reversely.

Upon the frame 33 above the mixing-drum 25 is secured in supporting hangers 34 a water-tank 35 supplied by a pipe 36, and delivering its contents by way of a depending pipe 37 to the interior of said mixing-drum through its receiving opening 26.

The numeral 28 denotes a delivery chute which is medially pivotally supported to the rear of said mixing-drum on brackets 29. The chute has its forward end projected into the interior of the drum through the rear opening 27, and is tiltatable by means of an arm 30. The forward part of said chute normally tilts downwardly into the drum. The lever-arm 30 is used to tilt the chute to elevate its forward part, which then receives the contents of the drum as the latter rotates, and delivers the same rearwardly into any desired receptacle.

My improved loading-device comprises an open-top vessel 51, and a tiltatable supporting slideway therefor. The vessel 51 is widest at its forward end which part receives the materials to be mixed, and is narrowed gradually toward its open rear end or lip 52. A bail 50 is pivoted to said vessel at the line of its center of gravity and has a medial ring 53 in which is secured the outer end of said cable 49.

The numeral 54 denotes a slideway for said vessel, comprising side members joined at the top fixedly by a plate 56 in an inverted V-shape. The members of said slideway have medial bent plates 55 which are pivotally mounted on the outer longitudinal faces of the frame-bars 1 to permit the slideway to be swung to its erect supporting position or to be swung up upon the frame. On the lower extremities of said members are pintles 64 pivoted in lugs 63 on disciform feet 62, the latter adapted to rest upon the supporting surface.

Upon said frame 1 are orificed lugs 61 to pivotally receive pintles 60 fixed on the lower end of an arm 59. The upper end of said arm has fixed pintles 58 adapted to enter and engage notches in lugs 57 on said slideway plate 56, to prop the apex of the slideway and to limit its rearward movement. Upon the bottom of the vessel 51 is a flat boss 68 to rest upon the apex of the slideway.

The numeral 65 denotes a fixed standard on said frame 1 having a bearing-opening for a pintle 67 upon which is pivoted a fixed lug on a plate 66, the latter serving to support the delivery end 52 of the vessel 51, when delivering its contents into said mixing-drum 25.

The vessel 51 may be loaded with the materials to be mixed, while on the ground on either side of the truck. The vessel is then hauled by the cable 49 up the adjacent inclined leg or member of the slideway 54 until it is at a proper height, its lip 52 then being directed rearwardly, the boss 68 seated on the apex of the slideway, and the vessel then tilted to direct its lip 52 into the front opening 26 of the mixing-drum to deliver its contents thereinto. The vessel may be then returned reversely for reloading.

When the slideway 54 is disengaged from the arm 59, the latter may be swung downwardly, and the former swung in a reverse direction to properly position them out of the way.

My improved loading-device with the V-shape slideway is useful in loading from either side of the truck as convenient.

Having described my invention, what I claim as new, and desire to secure by Letters Patent, is:

1. In combination, a transportable structure, an inverted V-shape slideway pivotally mounted on said structure with its members traversing opposite sides thereof, means mounted on said structure and releasably connected to said slideway for limiting its scope of movement in one direction, and a vessel slideable upon said slideway and tiltatable thereupon to deliver its contents into mixing apparatus mounted on said structure.

2. In combination, a transportable structure, an inverted V-shape slideway whose members are pivotally connected to opposite sides of said structure to depend therefrom when in an erected position, feet pivotally mounted on the lower ends of said members to rest upon the surface upon which said structure is supported when erected, an arm pivotally mounted upon said structure and releasably engaging said slideway to limit the movement of the latter in one direction, and a vessel slideable over either member of said slideway and tiltatable upon the apex of the latter to tilt its contents into mixing apparatus mounted on said structure.

3. In combination, a transportable structure, a power-plant mounted upon said structure, a tiltatable slideway having members extending to opposite sides of said structure, an open vessel slideable upon either member of said slideway and tiltatable thereupon to evacuate its contents into a mixing-device mounted on said structure, and power-transmission mechanism disconnectionably connected between said power-plant and said vessel to successively slide and lift the vessel upon said slideway and then tilt it thereupon to cause it to evacuate its contents into the mixing-device.

4. In combination, a transportable structure, a power-plant mounted upon said structure, a tiltable branched slideway on said structure, an open vessel slidable upon either branch of said slideway and tiltable thereupon to evacuate its contents into a mixing device mounted upon said structure, and power-transmission mechanism disconnectibly connected between said power-plant and said vessel to successively slide and lift the vessel upon said slideway and then tilt it thereupon to cause it to evacuate its contents into the mixing-device, and an arm pivotally mounted on said structure and having engaging means on its free end 15 to engage and limit movement of the slideway when the latter is in its erect position.

Signed at Waterloo, Iowa, this 16th day of May, 1919.

FRANK RUSSELL GLASENER.
